UNITED STATES PATENT OFFICE

ROBERT C. LIVESAY, OF MOLINE, ILLINOIS, ASSIGNOR TO DEERE & COMPANY, OF MOLINE, ILLINOIS, A CORPORATION OF ILLINOIS

GRAIN SHOCKER

Application filed March 9, 1929. Serial No. 345,787.

This invention relates to grain shockers of the type shown and described in Letters Patent No. 1,626,612, granted May 3, 1927, to C. C. Kellogg, and No. 1,652,280, granted December 13, 1927, to C. C. Kellogg and E. N. Kellogg, Jr. Such machines comprise means for receiving the bundles of grain from the binder deck of the harvester and depositing them in or upon a receiving frame or deck adapted to support the number of bundles required to make up a shock, and to be tilted to deposit such bundles on the ground back of the shocker, with their butt ends lowermost, in the form of a shock. Before the accumulated bundles are so deposited, they are bound together by an encircling loop of twine which is knotted by the operation of suitable knotting devices that form a part of the shocker mechanism. The devices by which the bundles of grain are transferred to the receiving deck are operated by power derived from a suitable source, such as the bull wheel of the harvester, or through a suitable power take-off on the tractor, where the implement is tractor drawn.

My present invention is concerned only with the receiving deck on which the pile of bundles that form the shock is accumulated, and the mechanism for tilting it to deposit the shock on the ground, and, therefore, it is to be understood that the other parts of the shocker as a whole may be of any suitable design, although I prefer to apply my improvements to shockers having the general construction shown and described in the patents hereinbefore mentioned, and, accordingly, in the accompanying drawings have exemplified them in that form of machine.

Those familiar with the art will understand that as the several bundles of grain are deposited in a pile on the receiving deck in an approximately horizontal position with their butt ends toward the rear, and to deposit the shock upon the ground, the receiving deck is turned to an approximately vertical position,—usually somewhat beyond a vertical position,—it is important that movement of the deck from its receiving to its discharging position be so accomplished as not to materially disturb or disarrange the several bun-

dles making up the pile. Usually the pile is made up of eight bundles, although the number may of course be varied, and if the receiving deck be started suddenly, disarrangement of the bundles is apt to result from the jar, and consequently when the shock is deposited upon the ground it may not stand firmly, or some of the bundles may fall away, thereby ruining the shock. Again, it is desirable that after the tilting movement of the receiving deck is started, its speed be accelerated until it reaches the dumping position, when it should be given a sudden impulse calculated to set the shock firmly on the ground in an upright position; also it is desirable that the return movement of the receiving deck be accomplished quickly, and that such return movement be slowed down as it approaches its initial or bundle receiving position to avoid slamming it down on the shocker frame, which might result in damage to some of the parts. These movements of the receiving deck are made in timed relation to the operation of other parts of the shocker, and, therefore, must be accurately controlled, and effected during uniform time intervals, and the prime object of my invention is to provide means by which the receiving deck may be actuated in the manner above pointed out as desirable. This object is accomplished as illustrated in the drawings and hereinafter described. What I regard as new is set forth in the claims.

In the accompanying drawings,—

Fig. 1 is a partial plan view of a shocker showing the receiving deck in its bundle receiving position, some parts being in section;

Fig. 2 is a longitudinal vertical section on line 2—2 of Fig. 1, also with the receiving deck in its initial or bundle receiving position;

Fig. 3 is a view similar to Fig. 2 with the receiving deck in its discharging position; and

Fig. 4 is a detail, being a partial vertical cross-section on line 4—4 of Fig. 2.

Referring to the drawings,—5 indicates the frame of the shocker, which is supported on ground wheels 6, 7 adjacent to the ends

thereof, as best shown in Fig. 1. These wheels are mounted on spindles 8, 9 carried by arms 10, 11, respectively, which arms are pivoted on vertical shafts 12, 13 so that they 5 may swing transversely to steer the wheels.

A connecting rod 14 connects the free ends of the arms 10, 11 so that they move in unison. Preferably, the shocker frame may be 10 vertically adjusted with respect to the wheel spindles in accordance with the level of the harvester associated therewith, as pointed out in Kellogg Patent No. 1,626,612, for which purpose an upright rack 15 is provided at each side of the shocker frame and 15 is carried by the wheel mounting. Each of these racks is engaged by a worm 16 at the lower end of a vertical shaft 17 journaled upon the shocker frame, as best shown in Fig. 4. The shafts 17 preferably extend up 20 through the vertical shafts 12, 13, which are tubular as shown in Fig. 1. The shafts 17 may be rotated to rotate the worms 16 by cranks 18 that engage their squared upper 25 ends, as shown in the latter figure.

25 Mounted on the shocker frame is a power shaft 19 which may be driven either from the bull wheel of the harvester through a suitable flexible connection, as described in said Kellogg patents, or may be driven in any 30 other suitable way. This power shaft carries a driving gear wheel 20, shown in Figs. 2 and 3, which meshes with a driven gear wheel 21, the latter being loosely mounted on a crank shaft 22 arranged parallel with the 35 power shaft 19. Connected with the driven gear 21 is a clutch member 23 that is fast with said gear, and is also loosely mounted on the crank shaft 22. Associated with the clutch member 23 is a clutch member 24 that 40 is fast on the crank shaft 22 and is adapted to be operatively connected with the clutch member 23 by any suitable means, such for example as that shown and described in Kellogg Patent No. 1,626,612.

45 The devices for operatively connecting said clutch members together are normally held out of operative position by the engagement of the lower arms 25 of a trip lever 26 with a dog 27 that forms a part of the clutch mechanism, as shown in Fig. 4. The trip lever 26 is pivotally mounted at 28 on the shocker frame, preferably on a bracket 29, and its arm 25 is normally held in position 50 to intercept the dog 27 and hold the clutch members out of operative engagement with each other by a spring 30, one end of which is connected with the trip lever 26 and the other end with an ear 31 that forms a part 55 of the bracket 29. The arrangement is the usual one by which when the trip lever is in its normal position it holds the clutch connecting devices controlled by the dog 27 out 60 of operative engagement with each other, but when said trip lever is actuated to move 65 its arm 25 out of engagement with the dog

27, the release of such dog connects the two clutch members 23, 24 together. The driven wheel 21 and clutch member 23 constantly rotate, and the clutch member 24 is normally stationary. Therefore, when the two clutch 70 members are connected the clutch member 24 rotates with the driven wheel 21 and consequently rotates the crank shaft 22. In practice the trip lever 26 is released immediately after it has been actuated, so that it 75 at once returns to its operative position and its arm 25 accordingly engages the dog 27 when the clutch member 24 has made one complete rotation, which disconnects it from the clutch member 23 and stops the rotation 80 of the crank shaft 22.

The trip lever 26 is actuated in timed relation to the operation of other parts of the shocker by means of an arm 32 carried by and 85 rotating with a shaft 33, which, in the present instance, is a horizontal shaft that forms a part of the drive for the knotter mechanism by which the bundles are tied. The arm 32 rotates about the axis of the shaft 33, and it is so arranged that in its rotary movement 90 it is adapted to engage an arm 34 carried by the trip lever 26, as shown in Fig. 4, to actuate said trip lever and throw the clutch mechanism into operation. The knotter shaft 33 may be driven in any suitable way, as for 95 example in the manner described in said Kellogg patents. The parts as thus far described are all old, and, therefore, they have been described only to the extent necessary to a 100 clear understanding of the improvements with which this application has to do.

Referring now more particularly to Figs. 2 and 3, 35 indicates the bundle receiving deck or platform, which is a frame of suitable form and construction to receive a pile of 105 bundles sufficient in number to make a shock. This receiving deck is pivotally mounted on the shocker frame to swing about a transverse axis, and is so located that it discharges 110 the shock rearwardly. In the illustrated construction it is mounted on a transverse shaft 36 secured to the rear portion of the shocker frame 5. As shown in said figures, the shaft 36 is located nearer the rear margin of the 115 deck 35 than its front margin, as usual.

120 Preferably, the deck is provided with a number of upright prongs 37, 38, 39, to aid in holding the bundles in position, as disclosed in the said Kellogg patents. The several bundles going to make up the shock are piled on the deck 35 with their butt ends to the rear, or to the right as shown in Figs. 2 and 3, and when the pile is completed the bundles are tied together by a loop of twine, 125 after which the deck is tilted to rock it about the shaft 36 as an axis to approximately the position shown in full lines in Fig. 3, thereby depositing the shock on the ground in an upright position. The prongs 37, 38, 39 are 130

withdrawn from the shock by the forward movement of the machine.

In building up the shock on the receiving deck 35 it is desirable that the pile be kept as nearly level as possible, and to compensate for the greater bulk of the butt ends of the bundles I provide for maintaining the receiving deck normally in an inclined position with its rear end lowermost, as shown in Fig. 2. This is accomplished through the operating connections by which the receiving deck is tilted, as will be presently explained.

The mechanism by which the receiving deck is rocked to its discharging position, and returned to its normal position after the shock has been deposited, comprises an arm 40 that is pivotally supported at its upper end upon a transversely disposed pivot 41 carried by a standard 42 that rises from the shocker frame, as best shown in Fig. 4. The upper end of said standard is braced by a brace 43.

The arm 40 hangs pendulous from the pivot 41 so that it may swing fore and aft adjacent to a crank 44 at the free end of the crank shaft 22, as best shown in Figs. 2 and 3. The crank 44 is provided with a wrist pin 45 which preferably carries a roller 46, and is arranged to travel in a longitudinal slot 47 in the arm 40. The lower portion of this slot is curved rearwardly as shown in said figures, and it will be understood that when the crank shaft 22 rotates the arm 40 will be swung fore and aft by the rotation of the wrist pin 45 about the axis of the crank shaft, and that by reason of the curvature of the slot 47 a differential movement will be imparted to the arm 40 so that its speed at different points in its stroke will be varied accordingly. The

lower end portion of the arm 40 is connected by a pitman 48 with the under side of the receiving deck 35 at a point back of its pivotal support 36, 49 indicating the point of connection of the pitman with the receiving deck 45 and 50 its pivotal connection with the arm 40. The pitman 48 is preferably made in two parts connected by a screw-threaded coupling 51, so that its length may be adjusted to regulate the normal position of the deck 35. Man-

ifestly, by increasing or shortening the length of the pitman the inclination of the receiving deck when in its normal position may be varied to meet diverse operating conditions, but its length should be such that the receiving deck is normally gently inclined to a sufficient extent to compensate for the extra thickness of the butt ends of the bundles so that the pile going to make up the shock will be level enough to make it stable.

As has been explained, it is desirable that the dumping movement of the receiving deck 35 be started slowly, and to that end the parts are so arranged with reference to each other that when the crank 44 starts to move after the clutch mechanism has been thrown into

operation, the roller 46 will at first travel in a part of the slot 47 that is curved approximately concentrically with the axis of the crank. Consequently, the movement of the roller 46 in the slot 47 will start the rearward movement of the arm 40 quite slowly. Shortly beyond the starting position, however, the curvature of the slot 47 approaches a radial position, so that the speed of the arm 40 is greatly accelerated until the full discharging position of the receiving deck is reached, at which time a final dumping impulse is given to it, to cause it to deposit the shock firmly and squarely on the ground. This position is shown in Fig. 3. After the shock has been discharged from the deck 35 and released from the prongs 37, 38, 39, the continued rotation of the crank carries its roller 46 into the upper straight portion of the slot 47, at which time said roller is traveling forwardly through the upper arc of its cycle, and the slot is more nearly in radial relation to such arc, with the result that the arm 40 is swung forward rapidly toward its initial position, but before it reaches such position the roller 46 will have moved downward in the slot 47 to a point where it is traversing a part of the slot that is more nearly concentric with the arc traversed by the roller, and consequently the movement of the arm 40 will be slowed down, so that it will stop gently when the trip mechanism disconnects the clutch members and stops rotation of the crank shaft 22. The receiving deck 35 will, therefore, be restored to its initial position without jar.

Thus the connections between the driven gear 21 and the pitman 48 constitute variable speed mechanisms by which the deck is tilted at varying speed notwithstanding the fact that the crank shaft rotates at substantially constant speed.

By controlling the tilting movement of the receiving deck in the manner described, when loaded the bundles are not apt to be disarranged or disturbed, the shock is deposited properly on the ground, and the receiving deck is returned quickly and smoothly to its initial position, so that there is little danger of damaging the operating parts.

Obviously, instead of providing the arm 40 with a slot, and the crank 44 with a pin and roller to move in such slot, the crank could be provided with a shoe to slide along a guide-way carried by the arm 40 and shaped to conform to the curvature of the slot, such being substantially a mere reversal of the arrangement shown. In other respects also my invention includes such changes or modifications as would occur to those skilled in the art.

I claim:

1. In a grain shocker of the type wherein bundles of grain are piled on a receiving deck adapted to be tilted to set the shock on the ground, the combination with a suitable

frame and a bundle receiving deck tiltably mounted thereon, of mechanism for tilting said deck comprising a crank, means for rotating the same, and means operatively connecting the crank with said deck including a member differentially actuated by said crank to start the tilting movement of the deck slowly, and then accelerate such movement to the point of discharge.

10 2. In a grain shocker of the type identified in claim 1, the combination with a suitable frame and a bundle receiving deck tiltably mounted thereon, of mechanism for tilting said deck comprising a crank, means for rotating the same, and means operatively connecting the crank with said deck including a member differentially actuated by said crank to start the tilting movement of the deck slowly, and then accelerate such movement to the point of discharge, and after the discharge of the shock to return the deck to its normal position, slowing down its movement as it nears the latter position.

25 3. In a grain shocker of the type identified in claim 1, the combination with a suitable frame and a bundle receiving deck tiltably mounted thereon, of mechanism for tilting said deck comprising a pitman operatively connected with said deck, an actuating device mounted on the frame, and means interposed between said pitman and said actuating device for differentially actuating said pitman to start the tilting movement of the deck slowly, and then accelerate such movement.

35 4. In a grain shocker of the type identified in claim 1, the combination with a suitable frame and a bundle receiving deck tiltably mounted thereon, of mechanism for tilting said deck comprising a pitman operatively connected with said deck, a crank mounted on the frame, means for rotating said crank, and means interposed between said pitman and crank for differentially actuating said pitman to start the tilting movement of the deck slowly, and then accelerate such movement.

50 5. In a grain shocker of the type identified in claim 1, the combination with a suitable frame and a bundle receiving deck tiltably mounted thereon, of mechanism for tilting said deck comprising a swinging member mounted on the frame, means for differentially actuating said swinging member to vary the speed thereof, and an operating connection between said swinging member and the deck.

55 6. In a grain shocker of the type identified in claim 1, the combination with a suitable frame and a bundle receiving deck tiltably mounted thereon, of mechanism for tilting said deck comprising a swinging member mounted on the frame, a crank, connecting means between said swinging member and said crank adapted to differentially actuate said swinging member to vary the speed

thereof, and an operating connection between said swinging member and the deck.

7. In a grain shocker of the type identified in claim 1, the combination with a suitable frame and a bundle receiving deck tiltably mounted thereon, of mechanism for tilting said deck comprising a swinging member mounted on the frame, a crank, connecting means between said swinging member and said crank adapted to differentially actuate said swinging member to vary the speed thereof, and a pitman connected with said swinging member and with the deck for tilting the deck by the swinging of said member.

75 8. In a grain shocker of the type identified in claim 1, the combination with a suitable frame and a bundle receiving deck tiltably mounted thereon, of mechanism for tilting said deck comprising a swinging member mounted on the frame, a crank, connecting means between said swinging member and said crank adapted to differentially actuate said swinging member to vary the speed thereof, and a pitman connected with said swinging member and with the deck for tilting the deck by the swinging of said member, said pitman being adjustable to vary the operative length thereof.

9. In a grain shocker of the type identified in claim 1, the combination with a suitable frame and a bundle receiving deck tiltably mounted thereon, of mechanism for tilting said deck comprising a swinging arm mounted on the frame and having a curved longitudinally extending slot, a crank engaging in said slot for swinging said arm by the rotation of said crank, and means operatively connecting said arm with said deck.

95 10. In a grain shocker of the type identified in claim 1, the combination with a suitable frame and a bundle receiving deck tiltably mounted thereon, of mechanism for tilting said deck comprising a swinging arm mounted on the frame and having a curved longitudinally extending slot, a crank engaging in said slot for swinging said arm by the rotation of said crank, and a pitman connecting said arm with said deck.

105 11. In a grain shocker of the type identified in claim 1, the combination with a suitable frame and a bundle receiving deck tiltably mounted thereon, of mechanism for tilting said deck comprising a swinging arm mounted on the frame and having a curved longitudinally extending slot, a crank engaging in said slot for swinging said arm by the rotation of said crank, and a pitman connecting said arm with said deck, said pitman being adjustable to vary the operative length thereof.

115 12. In a grain shocker of the type identified in claim 1, the combination with a suitable frame and a bundle receiving deck tiltably mounted thereon, of mechanism for tilting said deck comprising a crank mounted

70

on the frame, means for rotating said frame, an arm pivotally mounted at its upper end on said frame to swing fore and aft, a pitman connecting the lower end portion of said arm with the deck, and a differentially operating connection between said crank and said arm for varying the movement of said arm effected by the rotation of said crank.

13. In a grain shucker of the type identified in claim 1, the combination with a suitable frame and a bundle receiving deck tiltably mounted thereon, of mechanism for tilting said deck comprising an actuating element adapted to rotate at substantially constant speed, and variable speed mechanism interposed between said actuating element and the deck for effecting the tilting of the deck by an initially slow movement with subsequent acceleration of the speed thereof.

14. In a grain shucker of the type identified in claim 1, the combination with a suitable frame and a bundle receiving deck tiltably mounted thereon, of mechanism for tilting said deck comprising an actuating element adapted to rotate at substantially constant speed, and variable speed mechanism interposed between said actuating element and the deck for effecting the tilting of the deck by an initially slow movement with subsequent acceleration of the speed thereof, followed, after the shock has been discharged, by deceleration of the movement of the deck as it nears its normal position.

15. In a grain shucker of the type identified in claim 1, the combination with a suitable frame, and a bundle receiving deck pivotally mounted thereon and normally supported in a downwardly and rearwardly inclined position, of mechanism for tilting said deck comprising an actuating element adapted to rotate at substantially constant speed, and variable speed mechanism interposed between said actuating element and the deck for effecting the tilting of the deck by an initially slow movement with subsequent acceleration of the speed thereof.

16. In a grain shucker of the type identified in claim 1, the combination with a suitable frame, and a bundle receiving deck pivotally mounted thereon and normally supported in a downwardly and rearwardly inclined position, of mechanism for tilting said deck comprising an actuating element adapted to rotate at substantially constant speed, and variable speed mechanism interposed between said actuating element and the deck for effecting the tilting of the deck by an initially slow movement with subsequent acceleration of the speed thereof, followed, after the shock has been discharged, by deceleration of the movement of the deck as it nears its normal position.

ROBERT C. LIVESAY.
